UNITED STATES PATENT OFFICE.

JOHN SLATER, OF HANLEY, ENGLAND.

DESIGN FOR A PLATE.

SPECIFICATION forming part of Design No. 33,283, dated October 2, 1900.

Application filed September 8, 1900. Serial No. 29,463. Term of patent 7 years.

To all whom it may concern:

Be it known that I, JOHN SLATER, a subject of the Queen of Great Britain, residing at the borough of Hanley, in the county of Stafford, 5 England, have invented and produced a new and original Design for a Plate, of which the following is a specification, reference being had to the accompanying drawings, forming a part thereof.

10 In the said drawings, Figure 1 is a plan view of a plate showing my design. Fig. 2 is a vertical medial section of the same.

A continuous border A of figures resembling "x's" and "o's" forms the outer boundary 15 of the design, while at intervals are hung therefrom pieces of chain-like ornamentation B of equal length and having their ends joined at the points of meeting with the border A. These chain-like ornaments consist

of figures b, similar to the outer ones of the 20 border A, connected to each other by oblong figures b, resembling links. At the lowest point of each section is a centerpiece C, consisting of four "o's" or circles and a smaller "o" or dot in the center thereof. 25

The whole design forms a continuous band or border around the rim of the plate, the figures constituting the same being raised or embossed thereon.

What I claim is—

30 The design for a plate substantially as herein shown and described.

Signed at Buxslew, in the county of Stafford, England, this 28th day of August, 1900.

JOHN SLATER.

Witnesses:

F. BARRATT,

J. H. COPESTAKE.
